UNITED STATES PATENT OFFICE.

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE.

CORRUGATED STRUCTURE FOR RAILWAY CARS.

Application filed May 16, 1925. Serial No. 30,778.

- My invention relates to the construction of railway cars having parts formed of metallic plates which are subjected to lateral, buckling and sometimes torsional stresses.
- 8 Said parts are made of one or more metallic plates or panels formed with vertical or horizontal corrugations or other integral stiffening or bracing means to resist such stresses. While efforts are made to block 10 the lading in the car, the shocks caused by the heavy locomotives, the emergency air brake and the classification hump tear the lading away from its moorings and throw it against the end of the car, the lateral weaving of the car throws it against the side of the car, and the impact throws it against the bottom of the car. My invention is 15 adaptable to several parts of a railway car, such as side doors, side walls, floor sheets 20 (sloping or otherwise), hopper doors, roof sheets, etc., but it is especially adaptable for use as the end wall of a railway car and is also adaptable to box, gondola or other types of cars.
- 24 One of the objects of the invention is to provide metallic parts of a railway car, which have great strength to resist the torsional and weaving stresses which exist in a railway car when moving in service.
- 28 These stresses are caused by the inertia of the roof and superstructure when the train is suddenly stopped; rough or uneven track; the superelevation of the track on curves; the lateral inertia in rounding curves; eccentric thrust due to the lading being secured to one side of the car; the cars being "cornered"; the use of push pole pockets, etc. Such stresses rack and distort the superstructure which decreases the life of the car, 35 and also causes the car to leak grain, sand and other such material. Furthermore, such stresses cause leaky roofs and leaky and inoperative side and end doors.
- The tendency of an all metal end wall to 45 bulge is resisted partially by the corrugations, stiffening members or whatever means have been provided to transmit such stresses to the side wall or frame members of the car. Such tendency is also resisted by the corner 50 post of the car acting as a vertical beam supported at its top and bottom and sustaining
- a horizontal load; in other words, the bulging of the end would pull the opposite corner posts toward each other. This bulging also tends to pull the end (or side) plate 55 downwardly and the end (or side) sill upwardly. Another object of the invention is to reinforce the frame members against thrust perpendicular to their length by means forming a part of a corrugated or 60 otherwise reinforced metallic end wall.
- Since the corrugated metallic wall is braced against buckling it in itself has considerable resistance to the lateral stresses but the wall must be well secured to the 65 frame members, (post, sill and plate) in order to secure the co-operation between these frame members and between the metallic wall and the frame members. Another object of the invention is to obtain an 70 improved method of securing a corrugated metallic wall to the frame members of the car.
- In the drawings:

Fig. 20 shows a modified form of my invention.

Fig. 21 is a section on line 21—21 of Fig. 20.

5 Fig. 22 is a section on line 22—22 of Fig. 20.

Fig. 23 is an enlarged view of the corner post of Fig. 4 and its associated parts.

10 Fig. 24 is a fragmentary elevation of Fig. 23.

A part of the metallic plate is pressed to form a panel 14 surrounded by an integral part of the plate positioned angularly to the plane of the panel. If this surrounding 15 part constitutes the edges of the plate then it would technically be called a "flange". However, it may be provided with a laterally extending part (or flange 28—27) so that the "surrounding part" would then technically 20 be called a "web". This laterally extending part is not an element of the broader claims of this application, therefore, to avoid the use of two different words to designate the same element, in different claims, the word 25 "web" is used to designate that part of the plate surrounding the panel and positioned at an angle thereto whether it constitutes the edges of the plate or not.

It has been proposed to press the central 30 portion of a metallic plate (or plates) so as to form a continuous web surrounding a panel and to reinforce this panel by horizontal corrugations or other integral reinforcements which traverse the panel and terminate adjacent the opposite portions of the web. In such an arrangement the load upon 35 the horizontal corrugations is transmitted to the continuous web only through the intermediate means of the flat portion of the plate lying between the end of the horizontal corrugations and continuous web. It has also been proposed to press the central portion of a metallic plate (or plates) so as to form a web (supposedly) surrounding a 40 panel and to reinforce this panel by horizontal corrugations or other integral reinforcements which are the same depth as the web where they merge into it. In such an arrangement the web as a beam is destroyed. 45 In my construction the transverse corrugations destroy only a part of the value of the web, leaving a remaining portion which extends continuously around the panel to receive the stresses from the horizontal corrugations and to function as a beam and a stiffener. Such stresses are transmitted directly 50 to the remaining portion of the web.

That portion of the web between the corrugations serves as an excellent place for 55 an attaching bolt or rivet because a bolt or rivet so positioned then also restrains the corrugations against deflection. Furthermore, a bolt or rivet so positioned prevents the web from buckling as it has a tendency 60 to do when acting as a beam.

In the drawings the usual parts of the car are shown such as the end sill 1; end plate 2; side sill 3; side plate 4; side girth 5; corner post 6; side lining 7; side sheathing 8; end lining 9 and end fascia 10.

70 In my construction the central portion of the metallic plate 11 (or plates 11—12) is pressed to form a continuous web 13—16 surrounding a panel 14. This panel 14 is reinforced with corrugations 15 or integral ribs which traverse the panel (in the preferred form) and merge into a part of the opposite portions 16 of the continuous web. The remaining portion 26 of the continuous web 80 extends continuously and uninterruptedly on three (or preferably four) sides of the wall. This web receives the load from the corrugations and forms a beam or stiffener to prevent bulging in transmitting the load from the corrugations to the frame of the car. These remaining portions of the vertical parts 16 of the continuous web are prevented from buckling or deflecting by being formed integral with the horizontal parts 13 of the continuous web (preferably by radial portions 17.) The web preferably lies against the adjacent frame member, such as corner post 6, end sill 1 or end plate 2 and is secured thereto by bolts 18 which are 85 preferably positioned between the corrugations. Other means 19 are provided to secure the plate to the frame member which are preferably positioned in alignment with the corrugations. These two means may be used jointly or severally. The plate is secured to the end sill 1 by bolts 20—21 and to the end plate by bolts 22—23.

90 The corrugations may be made the same depth (as shown in Fig. 9) or a greater depth than the depression forming the continuous web but the corrugations are of less depth than the web 13—16 where they merge into it. The advantages of a continuous web in combination with the corrugations of great depth (and strength) may also be obtained by providing a series or plurality of shallow corrugations 24 adjacent the continuous web which merge into a lesser number of larger and deeper (therefore stronger) corrugations 25 adjacent the middle of the plate. These shallower and deeper corrugations may be so positioned and dimensioned that the length of the center line of the metal of the shallower corrugations (see Fig. 8) is the same as the length of the center line of the metal of the deeper corrugations (see Fig. 6) which is a material 100 manufacturing advantage, as it more evenly distributes the draw and stretch of the metal due to pressing the corrugations in the plate.

105 Figs. 11 to 19 inclusive show a form of the invention applied to a steel frame car wherein 40 is the end sill angle; 41 the end plate; 42 the corner post; 43 the side lining; 44 the side lining nailing strip; 45 the side sheath- 110 115 120 125 130

ing and 46 the end lining. The corner post 42 may be reinforced by diagonal braces 47 and 48 extending back toward the middle of the car which are secured to the side plate 5 and side sill, respectively.

In this form the end wall comprises two (or more) plates 49—50 secured together and each individual plate has its central portion pressed to form a continuous web 51 surrounding a panel 52 and the corrugations 53 are shown the same depth as the web for the major portion of their length but are of less depth than the web where they merge into it.

15 Figs. 20, 21 and 22 show another form of the invention wherein the central portion of an individual sheet is pressed to form a web surrounding a panel and the corrugations are of less depth than the web for their entire length.

Figs. 23 and 24 show an enlarged section of the corner post and illustrate the relation of the web 16, corrugations 24, and attaching bolts 18 and 19.

25 While I have shown and described the corrugations positioned horizontally, it is understood that the corrugations may extend vertically or otherwise, and still come within the scope of the invention, and, furthermore, 30 while I have described and claimed the wall made of "a plate," it is understood that it may be made of one or more united plates and still come within the scope of the invention.

35 I claim:

1. In combination with a railway car having corner posts, a metallic plate having a continuous web surrounding a panel provided with integral corrugations which merge into the opposite portions of said web but are of less depth than the web where they merge into it, said web being secured to the corner posts.

2. In combination with a railway car having corner posts, a metallic plate having a continuous web surrounding a panel provided with integral corrugations which merge into the opposite portions of said web but are of less depth than the web where they merge into it, said web provided with a continuous flange, said flange being secured to the corner posts.

3. In combination with a railway car having corner posts, a metallic plate having a continuous web surrounding a panel provided with integral corrugations which merge into the opposite portions of said web but are of less depth than the web where they merge into it, said web provided with a continuous flange, said web and said flange being secured to the corner posts.

4. In combination with a railway car having an end sill and an end plate; a metallic plate having a continuous web surrounding

a panel provided with integral corrugations 65 which merge into the opposite portions of said web but are of less depth than the web where they merge into it, said web being secured to the end sill and the end plate.

5. In combination with a railway car having an end sill and an end plate; a metallic plate having a continuous web surrounding a panel provided with integral corrugations which merge into the opposite portions of said web but are of less depth than the web 75 where they merge into it, said web provided with a continuous flange, said flange being secured to the end sill and the end plate.

6. In combination with a railway car having an end sill and an end plate; a metallic 80 plate having a continuous web surrounding a panel provided with integral corrugations which merge into the opposite portions of said web but are of less depth than the web where they merge into it, said web provided with a continuous flange, said web and said flange being secured to the end sill and the end plate.

7. In combination with a railway car having corner posts, an end sill and an end plate; a metallic plate having a continuous web surrounding a panel provided with integral corrugations which merge into the opposite portions of said web, but are of less depth than the web where they merge into it, said web provided with a continuous flange, said web and said flange being secured to the corner posts, the end sill and the end plate.

8. In combination with a frame member 100 of a railway car; a metallic plate pressed to form a panel portion with a web having a flange, said panel provided with integral corrugations which merge into said web, and means to secure said web to said frame 105 member.

9. In combination with a frame member of a railway car; a metallic plate pressed to form a panel portion with a web having a flange, said panel provided with integral corrugations which merge into said web but are of less depth than the web where they merge into it, and means to secure said web to said frame member.

10. In combination with a frame member 115 of a railway car; a metallic plate pressed to form a panel portion with a web having a flange, said panel provided with integral corrugations which merge into said web, and means to secure said web to said frame member positioned between said corrugations.

11. In combination with a frame member of a railway car; a metallic plate pressed to form a panel portion with a web having a flange, said panel provided with integral corrugations which merge into said web, but are of less depth than the web where they merge into it, and means to secure said web 125

- to said frame member positioned between said corrugations.
12. In combination with a frame member of a railway car; a metallic plate pressed to form a panel portion with a web having a flange, said panel provided with integral corrugations which merge into said web, means to secure said web to said frame member, and additional means to secure said flange to said frame member.
13. In combination with a frame member of a railway car; a metallic plate pressed to form a panel portion with a web having a flange, said panel provided with integral corrugations which merge into said web, but are of less depth than the web where they merge into it, means to secure said web to said frame member, and additional means to secure said flange to said frame member.
14. In combination with a frame member of a railway car; a metallic plate pressed to form a panel portion with a web having a flange, said panel provided with integral corrugations which merge into said web, means to secure said web to said frame member positioned between said corrugations, and additional means to secure said flange to said frame member, positioned in alignment with said corrugations.
15. In combination with a frame member of a railway car; a metallic plate pressed to form a panel portion with a web having a flange, said panel provided with integral corrugations which merge into said web but are of less depth than the web where they merge into it, means to secure said web to said frame member positioned between said corrugations, and additional means to secure said flange to said frame member positioned in alignment with said corrugations.
16. A metallic plate pressed to form a continuous web surrounding a panel, said panel provided with integral corrugations which merge into the opposite portions of the web, said corrugations being of less depth than the web where they merge into it.
17. A metallic plate pressed to form a continuous web surrounding a panel, said panel provided with integral corrugations which merge into the opposite portions of the web, said corrugations being of less depth than the web where they merge into it but of greater depth adjacent their middle.
18. A metallic plate pressed to form a continuous web adjacent its perimeter surrounding a panel, said panel provided with integral corrugations which merge into the opposite portions of the web, said corrugations being of less depth than the web where they merge into it.
19. A metallic plate having a continuous web surrounding a panel, said panel provided with integral corrugations which merge into the opposite portions of the web
- but are of less depth than the web where they merge into it, said web having a continuous flange surrounding it.
20. A metallic plate having a continuous web surrounding a panel, said panel provided with integral corrugations which merge into the opposite portions of the web but are of less depth than the web where they merge into it, said web having a continuous flange surrounding it substantially perpendicular to said web.
21. A metallic plate pressed to form a continuous web surrounding a panel provided with integral corrugations which merge into the opposite portions of the web and are of less depth than the web where they merge into it, said corrugations merging into a lesser number of deeper corrugations adjacent the middle of the plate.
22. A metallic plate pressed to form a continuous web surrounding a panel provided with integral corrugations which merge into the opposite portions of the web, said corrugations merging into a lesser number of deeper corrugations adjacent the middle of the plate, the length of the center line of the metal of the shallower corrugations being substantially the same as the length of the center line of the metal of the deeper corrugations.
23. A metallic plate pressed to form a continuous web surrounding a panel provided with integral corrugations which merge into the opposite portions of the web and are of less depth than the web where they merge into it, said corrugations merging into a lesser number of deeper corrugations adjacent the middle of the plate, the length of the center line of the metal of the shallower corrugations being substantially the same as the length of the center line of the metal of the deeper corrugations.
24. A metallic plate pressed to form a continuous web surrounding a panel provided with integral corrugations which merge into the opposite portions of the web and are of less depth than the web where they merge into it, said corrugations merging into a lesser number of deeper corrugations adjacent the middle of the plate.
25. A metallic plate pressed to form a panel with opposite webs having flanges, said panel provided with integral corrugations which merge into the webs but are of less depth than the webs where they merge into them.
26. A metallic plate pressed to form a panel with opposite webs having flanges, said panel provided with integral corrugations which merge into the webs but are of less depth than the webs where they merge into them, said corrugations merging into a lesser number of corrugations adjacent the middle of the plate.

27. A metallic plate pressed to form a middle of the plate, the length of the center panel with opposite webs having flanges, said line of the metal of the shallower corruga-
panel provided with integral corrugations tions being substantially the same as the 10
which merge into the webs but are of less length of the center line of the metal of the
5 depth than the webs where they merge into deeper corrugations.
them, said corrugations merging into a lesser
number of deeper corrugations adjacent the

GARTH G. GILPIN.
